UNITED STATES PATENT OFFICE.

THOMAS E. TAYLOR, OF MANSFIELD, OHIO, ASSIGNOR TO THE ECLIPSE STOVE COMPANY, OF MANSFIELD, OHIO, A CORPORATION OF OHIO.

COMBINATION COAL AND GAS RANGE.

1,347,601.

Specification of Letters Patent. Patented July 27, 1920.

Application filed May 2, 1919. Serial No. 294,158.

To all whom it may concern:

Be it known that I, THOMAS E. TAYLOR, a citizen of the United States, residing at Mansfield, in the county of Richland and State of Ohio, have invented certain new and useful Improvements in Combination Coal and Gas Ranges, of which the following is a specification.

My invention relates to improvements in combination coal and gas ranges, the primary object to combine in one stove or range structure coal and gas ranges, each complete in itself, the respective features of each being capable of complete operation independently of and without any interference with the other and without any change in the respective working parts.

A further and very important object of the invention is the provision of an improved range structure embodying an improved arrangement of coal and gas ovens together with improved coal and gas flues and an improved arrangement of the fire and gas burner boxes and of the up draft or chimney flue adapted to communicate either directly or indirectly with the fire box and provided with independent gas ports or vents adapted to communicate with the gas flues and burner.

A still further object is the provision of an improved arrangement of top gas burners and burner boxes or compartments therefor, said boxes or compartments being spaced from each other and arranged at the front and rear forming an intervening top coal flue extending over the median portion of said coal oven from the fire box to the opposite or end wall of the coal oven, the end and bottom walls of the coal oven being spaced from the stove casing forming communicating vertically and horizontally extending coal flues surrounding the coal oven, the horizontal or bottom coal flue communicating with the chimney flue at one side of and near the bottom of the coal oven.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part

of this specification, Figure 1, is a top plan view, partly in horizontal section, of a combination range constructed in accordance with this invention, a portion of the top or cover being broken away for the purpose of clearer illustration of the parts.

Fig. 2, a vertical longitudinal sectional view, taken on line 2—2, of Fig. 1.

Fig. 3, a transverse or cross sectional view, taken on line 3—3, of Fig. 2.

Fig. 4, a transverse or cross sectional view, taken on line 4—4, of Fig. 2.

The improved range structure comprises a suitable range casing 1, which may be of any suitable and convenient form, and is provided with oppositely arranged spaced coal and gas ovens 2 and 3, respectively.

A fire box 4, and ash pit 5, are interposed between the coal and gas ovens 2 and 3, and the fire box 4, may be provided with grates 4^a, and ash deflectors 5^a, adapted to discharge the ashes into an ash pan 5^b, held in place by means of ash pan guides 5^c.

The gas oven or compartment 3, is provided with a cover or burner plate 6, dividing the same into a lower or broiler oven 3^a, proper, and an upper or gas oven 3^b, proper, the gas oven, proper 3^b, being provided with side walls 3^c, spaced from the walls of the range casing forming intervening gas oven flues 7^a, of the indirect type, adapted to carry the products of combustion from the burner 7, below, about and over the walls of the gas oven, the products of combustion in the indirect oven flues 7^a, finally passing over the top wall of the oven through the top gas flue (see Fig. 4) and being then adapted to escape downwardly at the rear into the chimney flue 8, by means of the flue or draft opening 7^b.

The walls of the gas oven are provided with rack guides 3^d, and the walls of the broiler oven are provided with rack guides 3^e, and the gas burner 7, in the present instance, being of the ring type, may be supported by means of hanger brackets 7^c.

The burner plate or section 6, adapted to be heated by gaseous fuel, may be provided with a pot opening 6^a, and a lid 6^b.

As a means of providing for a direct draft from the fire box to the chimney flue, the latter is provided with a direct draft or port opening 8^a, the latter being adapted to be

controlled by means of a damper 8^h, adapted to be operated and controlled by means of a damper rod 8^e, leading forwardly to the front of the range and operating in a well known and obvious manner.

As a means of providing for communication with the indirect coal flues surrounding the coal oven, as hereinafter described, the lower end of the chimney flue 8, is provided with an indirect draft or port opening 8^a, at 10 the rear of the range casing and beneath the bottom portion of the coal oven 2.

As a means of providing adjacent top sections above the coal oven adapted to be respectively heated by solid and gaseous fuel, 15 the top wall of the coal oven is spaced below the range top or cover 9, and is provided with spaced partition plates 10^a, which latter, conjointly with the upper marginal edges of the range casing, form spaced 20 burner compartments or boxes 10, said burner compartments or boxes 10, being arranged at the front and rear of the range top and provided with ring burners 11, (in 25 the present instance four in number) the rear burners 11, being provided with feed necks 11^a, leading to the front and communicating with the manifold 12, said burner necks 11^a, being provided with the usual 30 mixer and gas valve mechanism, and so likewise the front ring burners 11.

The burner necks 11^a, are preferably covered by means of a cover plate 13.

As a means of venting the rear burners 11, 35 and burner compartments or boxes 10, the chimney flue is provided with a draft or port opening 8^e, (See Figs. 1 and 3) said port opening being controlled by means of a damper 8^f, controlled by means of a rock 40 shaft or rod 8^e, extending to the front of the range and provided with an operating handle 8^h.

It will be seen that the curved partition plates 10^a, of the burner compartments or 45 boxes 10, form an intervening top flue for the products of the solid fuel or coal and that the said top or coal flue 14, extends from the fire box over the coal oven to the wall of the latter opposite to the wall adjacent to 50 the fire box, and as a means of providing vertical and bottom coal flues, the walls of the coal oven are spaced from the walls of the range casing forming a vertical coal flue 15, communicating with the top flue 14, and 55 communicating at the bottom with a bottom or horizontal coal flue 16, the latter leading under the bottom of the coal oven and diagonally forward to the indirect draft opening 8^a, the products of combustion of the solid 60 fuel in the indirect flues 14, 15 and 16, taking the direction indicated by the arrows in Fig. 2, of the drawings, when the direct damper 8^b, is closed.

It will thus be seen that the coal and gas 65 ovens are independent of each other and that

each is provided with independent coal and gas flues, and it will likewise be observed that the rear burners 11 and rear compartments 10^a, are independently vented through the damper opening 8^e, and that the gas 70 burner 7, of the gas oven is vented through the indirect oven flues 7^a, and that the latter are placed in communication with the chimney flue through the indirect flue or draft opening 7^b.

The range may be provided with a high 75 shelf bracket 17, adapted to support an overhanging shelf 18, and the shelf structure and the adjacent oven wall may be provided with splasher members 19.

It will be observed that the chimney flue 8, is arranged at the rear casing wall and that the same extends diagonally thereover and the ends thereof overlap the walls thereof opposite the coal oven and gas oven 85 flues and are provided with the indirect draft or port openings 8^a and 7^b, to communicate therewith.

From the foregoing description taken in connection with the accompanying drawings, 90 it will be obvious that the arrangement of the independent coal and gas ovens with respect to the fire box and the arrangement of the coal and gas flues, as likewise the arrangement of the front and rear burners 95 and burner compartments on the top of the coal oven is particularly advantageous and enables the coal or gas range features to be operated independently of each other. It will also be obvious that in the operation of 100 the coal range the gas oven will be heated enough to make it a desirable warming closet.

It will also be seen that the fire box and the chimney flue, together with the indirect 105 openings 7^b and 8^a, are so located with respect to the coal and gas ovens that the latter may be economically heated by either solid or gaseous fuel, or both, without change in stove parts.

It should also be understood that the use 110 of the terms "coal" and "gas" with reference to the coal and gas features of the improved range has been one of convenience of expression rather than restriction, and that the term "coal" includes the products of combustion arising from such solid fuels as coal, coke, wood, and the like, and that the term "gas" includes such gaseous fuels as natural and artificial gas, vapors arising 115 from oil, and the like.

From the foregoing description, taken in connection with the accompanying drawings, the operation and advantages of my invention will readily appear.

Having thus described one of the embodiments of my invention, what I claim and desire to secure by Letters Patents, is,—

1. In a cooking range, a casing having coal and gas ovens on opposite sides of and 130

- heated by a fire box and provided with a chimney flue said casing having separate indirect coal and gas flues surrounding said coal and gas ovens, respectively.
- 5 2. In a combination range, a casing provided with coal and gas ovens surrounded by separate indirect flues, a fire box between said ovens and heating the latter, and a chimney flue having a damper opening communicating with said fire box and communicating with said indirect flues.
- 10 3. In a combination range, a casing, coal and gas ovens therein surrounded by separate indirect flues, a fire box between and in contact with said coal and gas ovens and adapted to heat the same, and a chimney flue having a damper opening intermediate its ends communicating with said fire box, and terminal openings communicating with said 20 indirect flues.
- 15 4. In a cooking range, a casing having coal and gas ovens spaced from each other and heated by means of an intervening fire box and ash pit, said ovens being surrounded by separate indirect flues, and said casing being provided with a chimney flue extending at the rear of said fire box and coal and gas ovens and provided with direct and indirect flues communicating with said fire 25 box and surrounding said coal and gas ovens, respectively.
- 30 5. In a cooking range, a casing having coal and gas ovens and an intervening fire box and ash pit, said ovens being spaced from said casing and the latter being provided with separate indirect flues, surrounding said ovens said casing being also provided with a chimney flue extending across the rear end of said fire box and having its ends terminating at the rear of said 35 coal and gas ovens, and said chimney flue being provided with intermediate and end ports communicating with said fire box and with said indirect flues surrounding said 40 coal and gas ovens, respectively.
- 45 6. In a combination range, the combination with a casing provided with oppositely arranged spaced coal and gas ovens, said casing being provided at one side with a chimney flue having direct and indirect draft openings, said direct draft opening communicating with said fire box, one of said indirect draft openings being arranged beneath said coal oven, indirect coal flues 50 surrounding the top, end and bottom walls of said coal oven, and separate gas burner sections arranged above said coal oven, one of said sections being provided with a draft port communicating with said chimney flue.
- 55 7. A combination range, comprising a casing provided with laterally spaced coal and gas ovens having independent coal and gas flues, a fire box between and in heating contact with said ovens, a chimney flue at one side of said casing extending partially across said ovens and provided with independent flue ports communicating with said coal and gas flues, respectively, and indirect coal flues surrounding said coal oven and communicating with said fire box and with 60 one of said flue ports below said coal oven.
- 70 8. A combination range, comprising a casing provided with laterally spaced coal and gas ovens having independent coal and gas flues, a fire box between and in heating 75 contact with said ovens, a chimney flue at one side of said casing and having its ends extending over said ovens terminating in flue ports communicating with said coal and gas flues, respectively, and an indirect coal 80 flue surrounding said coal oven and communicating with said fire box and with one of said flue ports at the rear of said casing below said coal oven.
- 90 9. In a combination range, a fire box and ash pit, coal and gas ovens surrounded by indirect flues and arranged on opposite sides of and heated by said fire box and ash pit, and a chimney flue having direct and indirect draft openings, said direct draft opening 95 communicating with said fire box, and said indirect draft openings being arranged above and below said coal oven, said indirect draft opening above said coal oven communicating with gas oven flues and the burner of said gas oven, and the other indirect draft opening communicating with said indirect coal flues surrounding said coal oven.
- 100 10. In a combination range, including a casing and a fire box and ash pit, coal and gas ovens arranged on opposite sides of and heated by said fire box and ash pit, said coal oven being surrounded by an indirect coal flue, gas burners and gas burner boxes on top of said coal oven, and a chimney flue having direct and indirect draft openings, said direct draft opening communicating with said fire box, and said indirect draft 105 openings being arranged above and below said coal oven, one of said draft openings above said coal oven communicating with said gas burner boxes and said gas oven flues, and said indirect draft opening below said coal oven communicating with 110 indirect coal flue surrounding said coal oven.
- 115 11. A combination range, comprising a casing provided with a fire box and ash pit and coal and gas ovens arranged on opposite sides thereof, said casing being provided with a chimney flue having a direct draft damper opening communicating with the rear end of said fire box and having its ends extending over the casing at the rear 120 of said coal and gas ovens and provided with indirect flue openings, said casing being provided with an indirect coal flue forming a loop surrounding said coal oven and communicating with said fire box and 125 130

one of said indirect flue openings beneath the inner bottom corner portion of said coal oven.

12. In a combination range, the combination with a casing provided with oppositely arranged spaced gas burner sections and spaced coal and gas ovens, said casing being provided at one side with a diagonally extending chimney flue having direct and indirect draft openings, said direct draft opening communicating with said fire box and being provided with a damper, one of said indirect draft openings being arranged beneath said coal oven, and the others communicating with said gas burner sections and gas oven, and indirect coal flues surrounding the top, end and bottom walls of said oven and communicating with said indirect draft openings.

13. A cooking stove, comprising an oven, a fire box, spaced burner compartments on top of said oven at the front and rear forming a top flue extending horizontally from said fire box over the median portion of said oven, a gas oven on the opposite side of said fire box, and having indirect surrounding gas flues, a chimney flue provided with a damper opening communicating with said fire box and provided with an inlet port communicating with said gas flues around said gas oven, a vertical flue extending along the oven on the side opposite said fire box, a bottom flue communicating therewith and passing under said coal oven and communicating with the bottom of said chimney flue, and a gas chimney port leading from one of said burner compartments to said chimney flue.

14. A cooking stove, comprising a coal oven, a fire box, a pair of spaced burner compartments on top of said coal oven forming an intervening top flue extending from said fire box over said coal oven, a broiler oven on the opposite side of said fire box and a superposed gas oven, a chimney flue provided with a damper opening communicating with said fire box and provided with an inlet port communicating with said gas oven, a vertical flue extending down along the coal oven on a side opposite the side adjacent said fire box, a bottom flue communicating with said vertical flue and passing under said coal oven and communicating with the bottom of said chimney flue, and a gas damper opening leading from said burner compartment to said chimney flue.

15. A combination range, comprising a casing having burner top sections spaced from each other forming an intermediate top flue for the products of solid fuel, oppositely arranged spaced coal and gas ovens in said casing, a fire box and ash pit interposed therebetween, said fire box being in heating proximity to said coal and gas ovens,

a chimney flue at one side of said casing extending across the ends of said coal and gas ovens, a direct draft damper opening communicating with said fire box, a vertical flue at that side of the oven opposite the fire box communicating with said top flue, a horizontal flue leading under the oven from said vertical flue and communicating with said chimney flue, a burner disposed in said gas oven, and gas oven burner flues leading from said burner to said chimney flue.

16. In a combination coal and gas range, the combination with a casing provided at one side with a broiler oven and a superposed gas oven, a fire box interposed between and adapted to heat said coal oven and said broiler and gas ovens, a chimney flue at one side of said casing provided with direct and indirect draft openings, said direct draft opening communicating with said fire box, and said coal oven being provided with an indirect coal flue passing over its median portion forming separate burner compartments above said coal oven, one of said burner compartments communicating with said chimney flue, down and bottom flues surrounding said coal oven and communicating with said indirect coal flue and one of said indirect draft openings, and said gas oven being provided with an outlet port communicating with said chimney flue.

17. In a combination coal and gas range, the combination with a casing provided at one side with a broiler oven and a superposed gas oven, a fire box and ash pit interposed between said coal oven and said broiler oven, said fire box being adapted to heat said coal and broiler ovens, a chimney flue at one side of said casing provided with direct and indirect flue openings, said direct flue opening being provided with a damper and communicating with said fire box, and said coal oven being provided with an indirect coal flue over its top having separate burner compartments, one of said burner compartments communicating with said chimney flue through one of said indirect flue openings, down and bottom flues adjacent said coal oven and communicating with said indirect coal flue at the top and said indirect draft opening at the bottom of said coal oven, and said gas oven being provided with a gas vent communicating with said chimney flue.

18. A combination range, comprising a casing having burner top sections spaced from each other forming an intermediate horizontal flue for the products of solid fuel, oppositely arranged spaced coal and gas ovens in said casing, a fire box interposed therebetween and adapted to heat the same, a chimney flue extending diagonally of said casing and over the adjacent walls of said coal and gas ovens, a direct draft opening

communicating with said fire box, a vertical flue at that side of the oven most removed from the fire box and communicating with said horizontal flue at the top, a horizontal flue leading under the oven from said vertical flue and communicating with said chimney flue, a burner disposed in said gas oven, and ports leading from one of said burner top sections and gas oven respectively to said chimney flue, whereby said ovens may be economically heated by either solid or gaseous fuel or both without change in stove parts.

19. In a cooking range, the combination with a casing having adjacent top sections respectively heated by solid and gaseous fuel, oppositely arranged coal and gas ovens in said casing, a fire box and ash pit interposed therebetween and in heating contact therewith, an up flue at one side of said casing and said gas and coal ovens, a direct draft damper opening communicating with said fire box, an indirect coal flue extending over said coal oven intermediate said gaseous fuel top sections, said coal oven having its walls spaced from said casing forming down and bottom coal flues communicating with said indirect coal flue, said bottom coal flue being provided with an indirect coal flue opening communicating with said up draft coal flue, and a gas vent damper opening communicating between said up draft coal flue and one of said gaseous fuel sections.

20. In a cooking range, the combination with a casing having adjacent top sections respectively heated by solid and gaseous fuel, oppositely arranged ovens in said casing adapted to be heated by solid and gaseous fuel, a fire box interposed between and adapted to simultaneously heat said ovens, an up or chimney flue at the side of said casing and the ends of said ovens, a direct draft damper opening communicating with said fire box from said chimney flue, an indirect flue for the products of the solid fuel extending over one of said ovens and intermediate said gaseous fuel heated top sections, said oven having its walls spaced from said casing forming down and bottom

flues communicating with said indirect flue, said bottom flue being provided with an indirect flue opening communicating with said chimney flue, and a gas vent damper opening communicating between said up draft 55 coal flue and one of said gaseous fuel sections.

21. A combination range, comprising a casing having oppositely arranged coal and gas ovens, a fire box interposed therebetween and adapted to heat the same, a chimney flue communicating with said fire box and provided with a flue opening communicating with the gas ovens at the upper portion of said casing, front and rear top 60 burner boxes spaced from each other forming a top flue extending over said coal oven from said fire box, a vertical flue extending down the side of said oven on the side opposite said fire box, a bottom flue passing 65 under said coal oven, a port placing the chimney flue in communication with the rear top burner box, and a damper adapted to open and close communication between the chimney flue and the fire box for forming direct or indirect drafts.

22. A combination range, comprising coal and gas ovens, a fire box therebetween and in heating proximity thereto, a chimney flue communicating with said fire box and provided with a flue opening communicating with the gas oven, top burner boxes spaced from each other forming a median top flue extending from said fire box to the opposite 80 wall of said coal oven, a vertical flue extending down the side of said oven on the side opposite and away from said fire box, a bottom flue communicating with said vertical flue and passing under said coal oven, a port placing the chimney flue in communication with the bottom flue, a damper opening and damper placing the chimney flue in communication with one of said top burner boxes, and a damper opening adapted to open and close communication between 85 the chimney flue and the fire box and forming direct and indirect drafts, respectively.

In testimony whereof I have affixed my signature.

THOMAS E. TAYLOR.
